UNITED STATES PATENT OFFICE.

PERLEY GILMAN NUTTING, OF WASHINGTON, DISTRICT OF COLUMBIA.

COLORIMETER.

1,026,878.

Specification of Letters Patent.

Patented May 21, 1912.

Application filed January 17, 1912. Serial No. 671,756.

(DEDICATED TO THE PUBLIC.)

To all whom it may concern:

Be it known that I, PERLEY GILMAN NUTTING, a citizen of the United States of America, and a resident of Washington, in the District of Columbia, have invented a new and useful Improvement in Colorimeters, and application for Letters Patent on said improvement is made under the act of Congress of March 3, 1883, chapter 143.

10 The invention herein described, if patented, may be used by the United States Government, or any of its officers or employees in prosecution of work for the United States Government, or by any other 15 person in the United States, without the payment to me of any royalty thereon.

The following description in connection with the accompanying drawings is a full, clear and exact specification of my improvement, such as will enable those skilled in the art to which it appertains to make and use 20 the same.

This invention relates to apparatus of the type used for determining uniquely the 25 character of an "unknown" light. As is customary in apparatus of this kind, the character of the emitted, transmitted, or reflected light is determined by comparing it with light of known character.

30 The invention relates more particularly to a colorimeter, not for measuring the percentage composition of red, green and blue (trichromatic analysis), but for ascertaining the wave-length of the dominant hue or 35 its complementary, together with the "pale-ness" of this hue: that is, the percentage of white light which is mixed with the light of the dominant hue. This may well be termed "monochromatic analysis." My complete 40 apparatus includes also a photometer of some known type, for measuring the intensity and luminosity of the unknown light.

45 So far as I am aware, the practical color-composition-measuring instruments heretofore designed have all been polychromatic: that is, the "known light" has been composed of rays passed through or reflected from a plurality of screens each of known color and paleness. Examples of such apparatus are found in the United States patents to Fujita, 961,852; to Ives, 894,654; in the German patents to Kallab, Nos. 193814, 198449, 205271, 220184 and 221413; in Circular No. 28 of the United States Bureau of Standards (Washington, Government Print-

ing Office, 1911); and in text books on color. Examples of (impractical) monochromatic instruments for matching color are found in Abney's "Colour Measurement and Mixture" (New York, E. & J. B. Young & Co., 1891); and in the Arons chromoscope, described in *Annalen der Physik*, vol. 33, pp. 799-833.

The object of the invention is to embody a method of color measurement which shall 65 be free from arbitrary reference standard screens or surfaces, in an apparatus whose adjustments and readings may be made with ease and exactitude.

Other objects of my invention will more 70 fully hereinafter appear and the novel features of the invention will then be pointed out in the appended claims.

Referring now to the diagrammatic drawings, wherein like reference characters represent like parts throughout the several views,

Figure 1 is a Maxwell color triangle, illustrating graphically the difference between the trichromatic analysis of the prior art 80 and my system of monochromatic analysis. Fig. 2 is a plan of my apparatus in one position, with a photometer. Fig. 3 shows the field viewed at E, with the arrangement illustrated in Figs. 2, 4 and 5. Fig. 4 is a 85 view in perspective of parts of the apparatus, looking in the direction of arrow 4, Fig. 2. Fig. 5 is a view similar to Fig. 4, showing the parts in a different position. Fig. 6 is a plan similar to Fig. 2, showing 90 two positions of collimator B. Fig. 7 shows the field viewed at E, with the arrangement illustrated in Fig. 6.

Referring to the Maxwell color triangle, RGB, Fig. 1, the location of the point x_s , representing the unknown spectral light X_s , is determined, according to the trichromatic analysis of the prior art, by measuring the intensities of the red, green and blue in the light of unknown color, these intensities being indicated by the relative lengths of the trilinear coordinates $x_s r$, $x_s g$, and $x_s b$. The size of the triangle indicates the absolute intensity of the unknown light. Instead of the trilinear coordinates of the point x_s , I 100 determine the polar coordinates α_s and Wx_s . The angle α_s between the radius vector Wx_s and a suitable reference line WO is a measure of the dominant hue of the light X_s . The length of the radius vector Wx_s repre- 110

sents the per cent. white impurity. In case α is such that the unknown lies within the purple portion WRB of the triangle RGB, the determination is made of the supplementary α_s of the angle α_p ; that is, if the unknown light is purple, hereinafter designated as X_p , the wave-length of the supplementary (represented by α_s) is measured.

Referring to Fig. 2, A, B and M are collimators each comprising a source of light L, a slit s for adjusting the amount of light entering the tube t, a pair of nicol prisms n, n, for dimming the light to the desired extent, and a lens l. O is an observing device comprising a tube t', a lens l' and a slit s'. The eye of the observer is at E. P is a dispersing prism. C is a Lummer-Brodhun photometer cube. White light from collimator M traverses the dispersing prism P and the part of it traversing also the central portion of cube C enters the observer's eye at E. Since but a narrow portion H of the spectrum made by prism P and traversing the lens l' reaches the eye through the slit s', the observer sees the whole inside portion of the field (Fig. 3) of but one hue. By rotating collimator M about a vertical axis through the center p of prism P, pure spectral light of any desired wave-length 30 may be obtained at E. A second position of collimator M is shown in dotted lines at M', Fig. 2.

In practice the six classes of unknown light are: I, emitted spectral light; II, 35 transmitted spectral light; III, reflected spectral light; IV, emitted purple light; V, transmitted purple light; VI, reflected purple light. As these six classes of unknown light require different adjustments of the 40 apparatus, they will be considered separately.

Case I. The arrangement for emitted spectral light is shown in Figs. 2, 3 and 4, except that the screen D_s is not used in this 45 case. At L (collimator A) is placed the source whose emitted light X_s is to be tested. The part of the light X_s which is reflected in the cube C constitutes the outer portion of the field (Fig. 3) viewed at E. 50 The known light is composed of light H of suitable wave-length from collimator M plus white light W from collimator B, totally reflected at the second face f of prism P. The intensities of lights H and W may be adjusted by means of slits s or nicols n, n, in collimators M and B respectively. After a match has been secured between the unknown light X_s and the mixture of white W and spectral hue H, the wave-length of 55 the spectral hue H is determined from the position of the collimator M or by means of a small auxiliary hand spectroscope (not shown) held at the eye slit s'. The intensities of lights X_s, W and H are determined 60 from (1) the width of slits s; or (2) the

angle between nicols n, n; or (3) most precisely by using a photometer such as the Whitman disk D, rotated about its axis G (by suitable means not shown), together with the standard lamp K. This enables 70 the light X_s to be uniquely specified by: (1) the wave-length of its dominant hue, which is the wave-length of light H; (2) the percentage of white impurity, which is the ratio of intensity of light W to light H; 75 (3) the luminosity, stated usually in meter-candles, determined as indicated above.

Case II. With transmitted spectral light, a source of white light is used at L (collimator A), and the unknown light X_s is 80 the light transmitted from collimator A through the screen D_s to be tested. The rest of the operation is as in case I.

Case III. With reflected spectral light, the collimator A is raised to the position shown in Fig. 5; the cube C is rotated 90° about the optical axis of the ocular as an axis, to the position shown in Fig. 5; and the screen D_s is replaced by the screen E_s, Fig. 5. White light from the collimator A, 90 Fig. 5, falls upon the screen E_s and the reflected rays reaching the cube C constitute the unknown light X_s. The rest of the operation is as in Case I.

Case IV. With purple unknown light, it 95 is necessary to determine the wave-length, not of the dominant hue, but of its complementary. The arrangement for emitted purple light is shown in solid lines, Figs. 6 and 7, except that the screen D_p is not 100 used in this case. At L (collimator B) is placed the source whose emitted light X_p is to be tested. This unknown light X_p is combined, at the second face f of prism P, with spectral light H from collimator M. 105 White light W from collimator A enters the cube C, and is matched at E against light X_p plus light H. The field viewed at E is shown in Fig. 7. The rest of the operation is as in case I. The result in the case of 110 purple unknown light is expressed as (1) the wave-length of the complementary H of the dominant hue of the unknown X_p; (2) the percentage of white impurity, as in case I; (3) the luminosity, as in case I. 115

Case V. With transmitted purple light, a source of white light is used at L (collimator B), and the unknown light X_p is the light transmitted from collimator B through the screen D_p to be tested. The rest 120 of the operation is as in Case IV.

Case VI. For reflected purple light, the collimator B, Fig. 6, is moved to the position shown in dotted lines at B' and the screen D_p is replaced by the screen E_p. White light from the collimator in the position B' falls upon the screen E_p and the reflected rays reaching the prism P and cube C constitute the unknown light X_p. The rest of the operation is as in Case IV. 125 130 135

The operation, briefly, consists in matching the unknown light against light of a pure spectral hue plus white light, unless the unknown light is purple. In the latter case, the unknown light plus light of a pure spectral hue is matched against white. In either case the wave-length of the spectral light and the intensities of all three lights are determined, and the result expressed as (1) a wave-length, (2) a per cent. white, and (3) a luminosity.

As many changes could be made in the above construction and many apparently widely different embodiments could be made without departing from the spirit thereof, I intend that all matter contained in the above description or shown in the accompanying drawings shall be interpreted as illustrative and not in a limiting sense.

Having fully described my invention, what I claim as new and desire to secure by Letters Patent is:

1. A method of determining the hue, purity and luminosity of a beam of light consisting in determining the wave-length of the dominant hue (or its complementary, as the case may be), the proportion that the white light in the unknown bears to the pure light of dominant hue therein, and the luminosity of said beam.

2. In combination, means for producing a beam of white light and two beams of colored light, means for matching as to hue and purity either of two of the three beams against the combination of the other two beams, and means for measuring the luminosities of all of said beams.

3. Means for producing a beam of light of unknown color, means for producing a beam of white light, means for producing a beam of light of any desired pure spectral hue, means for adjusting independently the intensities of all of said beams, means for combining said last-named beam with either of said first-named beams, and means for matching as to hue and purity the combined beams against the remaining beam.

4. Means for producing a first beam of light of known quality, means for producing a second beam of light, means for producing a third beam of light, one of the two last-named beams being white light and the other being the unknown light, means for combining the first and second beams, means for matching as to hue and purity the third beam against said combined beams.

5. Means for producing a first beam of light of known quality, means for producing a second beam of light, means for producing a third beam of light, one of the two last-named beams being white light and the other being the unknown light, means for combining the first and second beams, means for matching as to hue and purity the third beam against said combined beams, said

matching means comprising a photometer cube.

6. Means for producing a first beam of light of known quality, means for producing a second beam of light, means for producing a third beam of light, one of the two last-named beams being white light and the other being unknown light, means for combining the first and second beams, means for matching as to hue and purity the third beam against said combined beams, said matching means comprising a photometer cube and observing device.

7. Means for producing a first beam of light of known quality, means for producing a second beam of light, means for producing a third beam of light, one of the two last-named beams being white light and the other being unknown light, means for combining the first and second beams, means for matching as to hue and purity the third beam against said combined beams and means for measuring the luminosity of each beam.

8. Means for producing a first beam of light of known quality, means for producing a second beam of light, means for producing a third beam of light, one of the two last-named beams being white light and the other being unknown light, means for combining the first and second beams, means for matching as to hue and purity the third beam against said combined beams and a flicker photometer for measuring the luminosity of each beam.

9. Means for producing a first beam of light of known quality, means for producing a second beam of light, means for producing a third beam of light, one of the two last-named beams being white light and the other being unknown light, means for combining the first and second beams, means for matching as to hue and purity the third beam against said combined beams, and a Whitman disk with standard lamp for measuring the luminosity of each beam.

10. Means for producing a first beam of light of known quality, means for producing a second beam of light, means for producing a third beam of light, one of the two last-named beams being white light and the other being unknown light, means for adjusting independently the luminosities of all of said beams, means for combining the first and second beams, means for matching as to hue and purity the third beam against said combined beams.

11. Means for producing a first beam of light of known quality, means for producing a second beam of light, means for producing a third beam of light, one of the two last-named beams being white light and the other being unknown light, means for adjusting independently the luminosities of all of said beams, means for combining the first

- and second beams, means for matching as to hue and purity the third beam against said combined beams, said matching means comprising a photometer cube.
- 5 12. Means for producing a first beam of light of known quality, means for producing a second beam of light, means for producing a third beam of light, one of the two last-named beams being white light and the 10 other being unknown light, means for adjusting independently the luminosities of all of said beams, means for combining the first and second beams, means for matching as to hue and purity the third beam against said 15 combined beams, said matching means comprising a photometer cube and observing device.
13. Means for producing a first beam of light of known quality, means for producing 20 a second beam of light, means for producing a third beam of light, one of the two last-named beams being white light and the other being unknown light, means for adjusting independently the luminosities of all of said 25 beams, means for combining the first and second beams, means for matching as to hue and purity the third beam against said combined beams and means for measuring the luminosity of each beam.
- 30 14. Means for producing a first beam of light of known quality, means for producing a second beam of light, means for producing a third beam of light, one of the two last-named beams being white light and the other being unknown light, means for adjusting independently the luminosities of all of said 35 beams, means for combining the first and second beams, means for matching as to hue and purity the third beam against said combined beams and means for measuring the luminosity of each beam.
- 40 15. Means for producing a first beam of light of any desired pure spectral hue, means for producing a second beam of light, means for producing a third beam of light, one of the two last-named beams being white light and the other being unknown light, means for adjusting independently the luminosities of all of said 45 beams, means for combining the first and second beams, and means for matching as to hue and purity the third beam against said combined beams.
- 50 16. Means for producing a first beam of light of any desired pure spectral hue, means for producing a second beam of light, means for producing a third beam of light, one of the two last-named beams being white light and the other being unknown 55 light, means for combining the first and second beams, means for matching as to hue and purity the third beam against said combined beams and means for measuring the luminosity of each beam.
- 60 17. Means for producing a first beam of light of any desired pure spectral hue, means for producing a second beam of light, means for producing a third beam of light, one of the two last-named beams being white light and the other being unknown light, means for combining the first and second beams, means for matching as to hue and purity the third beam against said combined beams and means for measuring the luminosity of each beam.
- 65 18. Means comprising a dispersing prism for producing a beam of light of any desired pure spectral hue, means for producing a second beam of light, means for producing a third beam of light, one of the two last-named beams being white light and the other being unknown light, means for adjusting independently the luminosities of all of said beams, means for combining the first and second beams, means for matching as to hue and purity the third beam against said combined beams and means for measuring the luminosity of each beam.
- 70 19. Means comprising a dispersing prism for producing a beam of light of any desired pure spectral hue, means for producing a second beam of light, means for producing a third beam of light, one of the two last-named beams being white light and the other being unknown light, means for combining the first and second beams, means for matching as to hue and purity the third beam against said combined beams.
- 75 20. Means comprising a dispersing prism for producing a beam of light of any desired pure spectral hue, means for producing a second beam of light, means for producing a third beam of light, one of the two last-named beams being white light and the other being unknown light, means for combining the first and second beams, means for matching as to hue and purity the third beam against said combined beams, and means for measuring the luminosity of each beam.
- 80 21. Means comprising a dispersing prism for producing a beam of light of any desired pure spectral hue, means for producing a second beam of light, means for producing a third beam of light, one of the two last-named beams being white light and the other being unknown light, means for adjusting independently the luminosities of all of said beams, means for combining the first and second beams, and means for matching as to hue and purity the third beam against said combined beams.
- 85 22. Means comprising a dispersing prism and collimator relatively adjustable for producing a first beam of light of any desired pure spectral hue, means for producing a second beam of light, means for producing a third beam of light, one of the two last-named beams being white light and the 90

- other being unknown light, means for combining the first and second beams, means for matching as to hue and purity the third beam against said combined beams.
- 5 23. Means comprising a dispersing prism and collimator relatively adjustable for producing a first beam of light of any desired pure spectral hue, means for producing a second beam of light, means for producing a 10 third beam of light, one of the two last-named beams being white light and the other being unknown light, means for combining the first and second beams, means for matching as to hue and purity the third beam against 15 said combined beams, and means for measuring the luminosity of each beam.
24. Means comprising a dispersing prism and collimator relatively adjustable for producing a first beam of light of any desired pure spectral hue, means for producing a second beam of light, means for producing a third beam of light, one of the two last-named beams being white light and the 20 other being unknown light, means for adjusting independently the luminosities of 25

all of said beams, means for combining the first and second beams, means for matching as to hue and purity the third beam against said combined beams.

30

25. Means comprising a dispersing prism and collimator relatively adjustable for producing a first beam of light of any desired pure spectral hue, means for producing a second beam of light, means for producing a third beam of light, one of the two last-named beams being white light and the other being unknown light, means for adjusting independently the luminosities of all of said beams, means for combining the 35 first and second beams, means for matching as to hue and purity the third beam against said combined beams and means for measuring the luminosity of each beam.

40

In testimony whereof, I have signed my 45 name to this specification, in the presence of two witnesses.
